UNITED STATES PATENT OFFICE.

CLYDE C. DEEDS, OF TERRE HAUTE, INDIANA.

BOTTLE-CLOSURE.

1,101,687.

Specification of Letters Patent. Patented June 30, 1914.

Application filed July 15, 1913. Serial No. 779,203.

To all whom it may concern:

Be it known that I, CLYDE C. DEEDS, a citizen of the United States, residing at Terre Haute, in the county of Vigo and 5 State of Indiana, have invented certain new and useful Improvements in Bottle-Closures, of which the following is a specification.

My present invention relates to improvements in bottle closures, and is designed to 10 provide a cheap but efficient bottle closure for use with milk bottles, which will be durable and perform the functions required of a sanitary milk bottle closure.

The invention consists in a bottle closure 15 stamped from a single piece of paper or card board, and formed with novel means for locking and strengthening the disk or cap of the closure.

In the accompanying drawings I have 20 illustrated one complete example of the physical embodiment of my invention constructed according to the best mode I have so far devised for the practical application of the principles.

25 Figure 1 is a top plan view showing the mouth of a milk bottle with my improved cap or closure applied thereto. Fig. 2 is a vertical central sectional view of Fig. 1. Fig. 3 is a perspective view of the bottle 30 closure looking down upon the top. Fig. 4 is a similar view looking at the bottom of the closure.

The bottle closure is used with the universal type of milk bottle as depicted in 35 Fig. 2 wherein the neck 1 is formed with the shoulder 2 and the flaring mouth 3, and the bottle closure is adapted to be seated on the shoulder of the mouth. The bottle closure comprises a circular disk 4 formed with 40 an annulus or ring 5 on its under side at the edge thereof, and this ring forms a projecting annular shoulder 6 of double the thickness of the disk 4. This ring forms a

strengthening means for the disk as well as providing a seal to seat on the shoulder 2, 45 and lends rigidity and stability to the closure by stiffening the disk.

A flaring collar 7 rises from the shoulder or ring, and as will be noted it is of greater diameter at its mouth than at its juncture 50 with the ring 5. This collar may be flexible or inflexible and is designed to protect the mouth of the bottle from extraneous substances and keep it clean. The disk and shoulder or ring are preferably substantially 55 inflexible and form an efficient closure for the bottle, while the collar 7, which may be either flexible or inflexible provides a means by which the closure or disk may be lifted from the bottle. It will be noted that the 60 closure is an integer and it is stamped to shape under proper dies, the annulus being formed or pressed to shape by suitable means constructed for the purpose. The closure may be coated with paraffin or oil if desired 65 to make it waterproof or moisture proof, and when the edges of the ring, or its shoulder is forced down upon the shoulder of the bottle neck the contents of the bottle are effectively sealed against the admission of 70 undesirable foreign substances or matter.

Having thus fully described my invention, what I claim is:—

An integral bottle closure comprising a flat disk and an upwardly and outwardly 75 flaring collar, and an annular shoulder projecting below the plane of the disk and laterally beyond the lower portion of the flaring collar.

In testimony whereof I affix my signature 80 in presence of two witnesses.

CLYDE C. DEEDS.
